BEAM COMPASS

Albert Ackron, Chicago, Ill.

Application August 19, 1937, Serial No. 159,813

6 Claims. (Cl. 33—27)

This invention relates to a compass and more particularly to an extensible beam compass for draftmen's use, although certain features thereof may be employed with equal advantage for other purposes.

It contemplates more especially the provision of an efficient, light, dependable and inexpensive extensible compass for describing circles of large diameter that is beyond the limitations of the ordinary compass now in general use.

Numerous types of compasses have heretofore been proposed for varied purposes, but these are not entirely satisfactory in describing unusually large circles beyond eight to twelve inches in radius. Then, too, beam compasses have heretofore been used wherein rigid wood beams are employed and each compass is supplied with a plurality of beams of different lengths so that one can be substituted for the other in describing circles of the desired size. Such a device is objectionable for numerous reasons, and it is the purpose of the present invention to provide an improved extensible compass that is graduated so that circles may be described of almost limitless size without resort to extraneous rulers or entailing a great deal of care in setting such to the desired radius prior to describing the circle.

One object of the present invention is to simplify the construction and improve the operation of devices of the character mentioned.

Another object is to provide an improved extensible beam compass that is light, simple, and inexpensive in construction and effective in use. Still another object is to provide an improved beam compass having calibrations to afford the immediate and accurate setting of the component parts to describe large size circles without entailing any appreciable time in the adjustment thereof.

A further object is to provide a beam compass having increased flexibility for describing circles of predetermined size with means for readily rendering such extensible or collapsible depending upon the requirements of any particular drawing.

A still further object is to provide a beam compass providing a sectional calibrated beam to describe circles of varying size from the smallest to the very largest without entailing any appreciable time, effort or care in the manipulation thereof.

A further object is to provide a beam compass having improved attachments for describing either pencil or ink circles of small or large

size depending upon the requirements of any particular drawing.

Other objects and advantages will appear from the following description of an illustrative embodiment of the present invention.

In the drawing:

Figure 1 is a perspective view of a device embodying features of the present invention, parts thereof being broken away to clarify the showing.

Figure 2 is a fragmentary view of the forward end of the beam shown in Figure 1.

Figure 3 is a fragmentary sectional view taken of the forward end of the tubular member comprising a part of devices embodying features of the present invention.

Figure 4 is a view in elevation of a handle attachment and the fulcrum point for a beam compass involving features of the present invention.

Figure 5 is a fragmentary sectional view in elevation of a compass attachment embodying features of the present invention.

Figure 6 is a perspective view of a part of a sectional beam embodying features of the present invention.

Figure 7 is an end view in elevation of a modified beam compass embodying features of the present invention.

Figure 8 is a perspective view of a still further modified sectional beam constituting a substitute for the section shown in Figure 6.

The structure selected for illustration comprises an elongated tubular metallic member 10, preferably though not essentially of cylindrical configuration to telescopically receive a beam 11 of substantially the same length for extensible association therewith. The beam 11 is preferably a metallic bar of polygonal cross-section, in the preferred form of rectangular cross-section, to provide flat surfaces for the permanent impression of various dimensional calibrations 12, 13, and such additional scales on the remaining surfaces as commercial practice may dictate.

For that matter the beam 11 may be of triangular (Figure 7) or hexagonal (Figure 8) configuration depending upon the required facility to provide different scales to render the use of the relatively telescopic members 10 and 11 more effective, speedily adjustable, and accurate in their use to describe circles having a radius within their limits of collapsible and extensible association. It is preferable though not essential to reinforce the ends of the tubular member 10 by swaging or providing end sleeves 14 and 15 that

are pressed or otherwise secured thereto in any suitable manner.

To maintain the relatively extensible and collapsible telescopic members 10 and 11 in any predetermined adjustable position, a threaded stud 16 engages a correspondingly threaded aperture in the sleeve 15 and tubular member 10 so as to project radially therethrough to engage a surface of the beam 11, thereby precluding relative rotation between the telescopic members 10 and 11 as well as retain such in any adjusted position. The threaded stud 16 may constitute the extremity of a needle pointed rod 17 having an internally threaded knurled engaging coupling sleeve member 18 formed integral with the needle pointed rod 17.

The needle pointed rod 17 may alternately serve as a fulcrum point or as a handle in displacing the telescopic members 10-11 about its extreme fulcrum 19 having internally threaded coupling sleeve 20 in detachable threaded connection with a threaded stud 21 anchored in and radially projecting from the reinforcing end collar 14 of the tubular member 10. It will be noted that the needle pointed fulcrum rod 19 projects from the end collar 14 in a diametrically opposite direction to the alternate handle and fulcrum engaging stud 16. A special handle member 22' (Figure 6) and 22'' (Figure 8) may be substituted for the needle pointed rod 17 (Figure 1) to render the manipulation thereof more effective.

In order to describe or circumscribe a circle of any predetermined radius determined from the scales 12 and 13, a pencil or pen or combination point 23 of any suitable construction is detachably associated with the extremity 24 of the beam 11, there being a threaded stud 25 extending axially from the extremity 24 of the beam 11 to receive and secure the confronting plates 26 and 27 of the combination pencil and pen point 23. To secure the confronting plates 26-27 in proper position, a threaded nut 28 engages the stud 25 to hold the plates 26-27 with their offset 29 against the correspondingly shaped extremity 24 of the beam 11, plate offsets 29 and beam extremity 24 being complementary to each other so as to preclude relative rotation and provide for their retention in alignment with the fulcrum 19 and handle engaging stud 16.

A pencil lead 30 is retained between arcuately curved confronting extremities 31 and 32 of the confronting plates 23 having their opposite confronting extremities 33 and 34 suitably bowed to retain ink therebetween. The bowed extremities 33 and 34 are rendered adjustable to define the line thickness inscribed therewith, and to this end a threaded stud 35 is anchored to the plate 26 to project through the plate 27 for receiving a nut 36 in threaded engagement therewith. It will be noted that the customary pencil or pen point 37 (Figure 8) having a threaded shank 38, may be secured to the beam 11 (Figure 1) or 11'' (Figure 8) by extending through a vertical aperture 39 (Figure 1) and 39'' (Figure 8) for threaded engagement by a pencil point 40 having an internally threaded coupler shank 41 which engages the threaded pen point shank 38 with the beam 11'' disposed therebetween.

As shown in Figures 6 and 8, a secondary beam 11' and 11'' may be provided with the pencil and pen point securing aperture 39' and 39'', respectively, or the axial stud 25'-25'' and threaded

nut 28'-28'' or both. Then, too, a sleeve or collar 15' and 15'' is disposed over each of the secondary beams 11' and 11'' to carry a needle pointed fulcrum 19' and 19'' in threaded engagement therewith. A handle member 22' and 22'' has a threaded extremity to threadedly engage a correspondingly threaded aperture provided in the collar 15' and 15'' in radial alignment with the fulcrum point 19' and 19''. The threaded handle extremity projects beyond the interior of the collars 15' and 15'' to engage the beams 11' and 11'', thereby precluding relative rotation therebetween. The secondary beams 11' and 11'' may be used alone for describing small circles or such may constitute a section for axial end alignment with a corresponding shaped and sized primary beam 11. To this end, the secondary beam 11' is provided with a threaded axial bore 42 (Figure 6) in the free extremity thereof to threadedly engage the stud 25 projecting from the primary beam extremity 24 to render such longer in size and sectional in construction.

In Figure 4 there is shown a detail view of a handle member 22' (see Figure 6) that has a reduced threaded extremity 21' to detachably engage a needle pointed rod 19' having an internally threaded coupler sleeve 20'. These parts may be assembled with a beam sleeve 15' disposed therebetween for the specified purpose. In Figure 5 a modified line pen 23' consists of symmetrical confronting plates 26' and 27' punched from a single die to present upstanding confronting extensions 31' and 32 to receive a handle 22' therebetween (Figure 5) or a pencil lead 30 as shown in Figure 1. A threaded stud 25' having a nut 28' retains the plates 26'-27' in assembled relation by projecting through the inwardly offset region 29' thereof that registers with the beam extremity 24'. In Figure 7, a triangular beam 11'a is substituted for the other polygonally-shaped beams described supra. The remaining parts are essentially similar to those described in connection with the other embodiments which need not be specifically described.

With the arrangement of parts above described, it will be apparent that the tubular elongated member 10 may desirably have a longitudinal distance of ten inches or any multiple thereof from the center or fulcrum point 19 to the extreme outer edge of its forward reinforcing collar or sleeve 15 so that the graduations 12 and/or 13 will measure the actual distance from the pencil or pen point 23 as shown on the solid telescopic bar 11 plus the ten inches or any predetermined multiple thereof defined by the tubular member 10.

As set forth in Figure 1, the radius defined by the members 10-11 from the fulcrum point 19 to the writing point 23 would be twelve inches; however, this may be varied depending upon the tubular member 10 and the calibrations 12 or 13. To procure an extension of the radius defined by the members 10-12 without unduly lengthening the complementary elements, the sectional or supplemental beam 11' may be fixed to the extremity of the primary beam 11 by having the foremost threaded end aperture 42 engage a correspondingly threaded stud 25 fixed to the extremity of the beam 11. For that matter, the supplemental beam 11' may be used independently to describe small circles where it would be too awkward to resort to the comparatively long members 10-11 to accomplish the intended purpose. This is clearly illustrated in Figure 8 and 75

affords the use of the device for small circles as well as unusually large circles, thereby rendering such unusually flexible in use.

It will be observed that the beam 11 may be of any desired configuration depending upon the dictates of commercial practice and the number of graduations that are desired for use in connection therewith. The beam 11 cannot be rotated relative to the tubular member 10 after they are adjusted to their desired position, since the handle or fulcrum shank 16 not only retains the telescopic members 10-11 in adjusted position but also precludes relative rotation therebetween. Any suitable supplemental guide means may be provided between the members 10-11 should commercial practice so dictate.

With the arrangement of parts above described, the pen point 23 or 23' can be readily separated to facilitate cleaning, and such may be used independently of the beam compass in conjunction with the handle 22' as an ordinary ruling pen. Then, too, the beam 11 may be removed from the tubular member 10 and the pen 23 disconnected therefrom so that the scales thereon may be used in the form of an ordinary ruler as occasion may require for various purposes in connection with the preparation of drawings.

The pen 23 may be reversed in direction (Figure 1) and a metallic point substituted in lieu of the pencil point 30 thereby rendering the use of the device as dividers for a large range of purposes. For that matter, a sheet metal cutting implement may be substituted for the pen 23 so that circles and arcs can be cut from sheet material such as leather, rubber, paper or thin metallic sheets. This also provides a good layout tool for carpenters, machinists and other technicians who find it necessary to describe arcs and circles in the skilled execution of their work.

A simple and inexpensive combination device has been provided that has a wide range of uses and facilitates the drawing of circles of large diameter which heretofore has been accomplished with large instruments that rendered their manipulation very difficult. Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. In a beam-type compass, the combination with an elongated member, of another elongated member operatively connected to said first named elongated member for longitudinal slideable movement relative to each other, a center point associated with an extremity of one of said elongated members, a line writing point associated with the opposite extremity of the other of said elongated members, and another center point associated with said elongated member intermediate said first named center point and said line writing point for reversible interchangeable use of said center points as handles in describing circles of substantially different diameters.

2. In a beam-type compass, the combination with an elongated tubular member, of another elongated member telescopically disposed within said first named elongated member for longitudinal slideable movement relative to each other, a center point associated with an extremity of one

of said elongated members, a line writing point associated with the opposite extremity of the other of said elongated members, and another center point associated with said elongated member intermediate said first named center point and said line writing point for reversible interchangeable use of said center points as handles in describing circles of substantially different diameters.

3. In a beam-type compass, the combination with an elongated tubular member, of another elongated member telescopically disposed within said first named elongated member for longitudinal slideable movement relative to each other, a center point detachably associated with an extremity of one of said elongated members, a line writing point detachably associated with the opposite extremity of the other of said elongated members, and another center point associated with said elongated member intermediate said first named center point and said line writing point for reversible interchangeable use of said center points as handles in describing circles of substantially different diameters.

4. In a beam-type compass, the combination with an elongated member, of another elongated member operatively connected to said first named elongated member for longitudinal slideable movement relative to each other, a center point associated with an extremity of one of said elongated members, a reversible line writing point associated with the opposite extremity of the other of said elongated members, and another center point associated with said first named elongated member intermediate said first named center point and said line writing point, said center points being fixedly spaced along said first named elongated member and extending from opposite sides thereof for reversible interchangeable use of said center points as handles in describing circles of substantially different diameters.

5. In a beam type compass, the combination with an elongated tubular member, of another elongated member telescopically disposed within said first named elongated member for longitudinal slideable movement relative to each other, a center point associated with an extremity of one of said elongated members, a line writing point associated with the opposite extremity of the other of said elongated members, and another center point threadedly associated with said first named elongated member intermediate said first named center point and said line writing point, said center points being fixedly spaced along said first named elongated member and extending from opposite sides thereof, said last named threadedly associated center point engaging said second named elongated member to maintain said elongated members in adjusted spaced relation for reversible interchangeable use of said center points as handles in describing circles of substantially different diameters.

6. In a beam-type compass, the combination with an elongated tubular member, of another elongated member telescopically disposed within said first named elongated member for longitudinal slideable movement relative to each other, a center point associated with an extremity of one of said elongated members, a line writing point associated with the opposite extremity of the other of said elongated members, a scale inscribed on said second named telescopic elongated member to indicate the radial length be-

tween said line writing point and both of said center points, and another center point threadedly associated with said first named elongated member intermediate said first named center point and said line writing point, said center points being fixedly spaced along said first named elongated member and extending from opposite sides thereof, said last named threadedly

associated center point engaging said second named elongated member to maintain said elongated members in adjusted spaced relation for reversible interchangeable use of said center points as handles in describing circles of substantially different diameters. 5

ALBERT ACKRON.
